UNITED STATES PATENT OFFICE.

VERNON L. TANNEHILL, OF FORT WAYNE, INDIANA, ASSIGNOR TO FORT WAYNE ENGINEERING AND MANUFACTURING CO., OF FORT WAYNE, INDIANA.

WATER SOFTENER.

Application filed August 9, 1926. Serial No. 128,065.

This invention relates to water softeners. Objects of this invention are to provide a

water softener which employs zeolites or similar material for softening the water, and 5 in which provision is made for regeneration of the zeolite after it has served its purpose during one period of operation so that the apparatus can be used continuously with a simple addition of ordinary chemicals, such 10 as common salt, for instance.

Most particularly, objects of this invention are to provide a water softening apparatus in which a novel mode of washing the zeolite and the interior of the softener 15 is provided so that all portions of the unused salt or other foreign materials may be easily and effectively extracted and carried to the discharge pipe.

Further objects are to provide a water 20 softening apparatus in which the washing is accomplished by causing the water to flow through the zeolite first in one direction and then in the other direction, so that the zeolite is most thoroughly freed from all unused 25 salt or other foreign material.

Further objects are to provide a novel 30 form of water softener which may be readily installed without requiring any valves located at its lower portion, but which may be mounted directly upon a vase with the valves and the pipe in relatively elevated position.

An embodiment of the invention is shown 35 in the accompanying drawings in which:

The single figure is a sectional view 40 through the water softener showing the pipe connections and showing by the three systems of arrows the several paths followed by the water.

Referring to the drawing, it will be seen 45 that the water softener comprises a vertical tank 1, preferably of cylindrical construction, which is provided with a top 2 equipped with a removable cap 3 held in place by means of a clamp 4. The bottom of the tank 5 is closed by a cup-shaped base portion which is provided with a central member 6. This member is symmetrical about the axis of the tank and forms a sharp, upwardly 60 directed cusp located exactly upon the axis of the tank, as illustrated in the lower sectional portion of the drawing.

Immediately above this cusp or pointed central bottom member 6, the flared mouth 7 of a pipe 8 is positioned. This pipe leads

centrally upwardly and passes outwardly, as indicated at 9.

Further, it is to be noted that a perforated plate or similar member 10 is carried by angle irons or by a flange 11 and itself carries a 60 screen or similar member 12. The zeolite is positioned upon this screen 12 and is indicated by the reference character 13. This zeolite does not completely fill the tank 1, but stops approximately at the point indicated by the reference character 14.

The pipe comprises a main supply pipe 15 leading from the water supply, and a main outlet or delivery pipe 16, and an exhaust pipe or discharge pipe 17. The pipe 70 15 communicates with a pair of pipes 18 and 19 controlled by valves 20 and 21. The pipe 18 extends to the pipe 9 and also to the discharge pipe 17, communication with the discharge pipe 17 being controlled by the valve 22. The discharge pipe 17 is connected with the pipe 19 and with the pipe 16 by means of the pipe 23, such latter pipe being controlled by the valve 24. It is to be noted also that a pipe 25 leads upwardly from the pipe 19 and enters the upper portion of the tank 1. Further, it is to be noted that a test valve 26 communicates with the delivery pipe 16.

In using the apparatus the water normally passes, as shown by the heavy arrows, through the pipe 15, past the valve 20, through the pipe 8, downwardly below the zeolite, and is deflected uniformly by the pointed central member 6, and its direction 90 reversed by the curved bottom portion of the tank so that it flows upwardly through the tank in a very uniform and even manner through the zeolite. It passes from the upper portion of the tank by way of the pipe 25 to the delivery pipe 16. This is the normal operation of the apparatus and the normal direction of flow of the water.

When it is desired to regenerate the zeolite, the cap 3 is removed and salt or a salt 100 solution is placed within the tank 1 through its upper opening, the supply of water being cut off from the tank during this operation and, preferably, the delivery pipe also being closed by means of the valve 27.

After this salt has acted upon the zeolite for approximately twenty minutes, the valve 21 is opened, the valve 20 being preferably closed during the insertion of the salt. The water now flows, as indicated by 105

the light full line arrows past the valve 21, up the pipe 25, into the upper portion of the tank, and downwardly through the zeolite. This downward flowing stream of water sweeps all of the unused salt and the excess salt solution into the funnel-like portion 7 of the pipe 8, due to the cup shape contour of the bottom of the tank, and due to the shape of the member 6. This excess material and the flowing stream of water passes upwardly through the pipe 8, through the pipe 9, and past the open valve 22 to the discharge pipe 17. After this process has continued the requisite length of time, the direction of flow of the water is reversed by closing the valve 21 and opening the valves 20 and 24. The water now flows, as indicated by the dotted line arrows, past the valve 20, through the pipes 18, 9 and 8 downwardly to the bottom portion of the apparatus, and is uniformly deflected upwardly by the cusp central-like member 6, and the curved bottom portion of the tank. The water thus passes uniformly upwardly through the zeolites and causes such zeolites to boil or stir, thus freeing any excess salt or salt solution or foreign matter, and this material passes outwardly through the pipe 25 to the pipe 23, the valve 24 being open and thus passing to the discharge pipe 17.

Testing of the water is easily secured by opening the test valve 26, when desired.

After this operation has continued the requisite length of time, the valve 24 is closed and the valve 27 is opened. The water now passes through the valve 20, through the pipes 18, 9 and 8, to the lower portion of the apparatus. It passes upwardly through the zeolites discharging through the pipe 25 to the delivery pipe 16.

It will be seen that a novel form of water softener has been provided in which a most thorough cleansing of the zeolite is secured with consequent assurance of absolute freedom from any excess salt, salt solution, or from any foreign material.

Further, it will be seen that this invention provides for a double direction of flow of the washing water and insures the correct agitation of the zeolite for its most effective use.

It will be seen further that the device may be mounted directly upon a base, as

there are no lower or bottom valves. Instead, all of the valves and the piping are located in an elevated portion with respect to the tank. Thus the device lends itself to easy installation and to easy access with reference to the controlling valves.

It will be seen further that the device may be very simply and economically made, and will be effective in operation.

Although the invention has been described in considerable detail, such description is intended as illustrative rather than limiting as the invention may be variously embodied and as the scope of such invention is to be determined as claimed.

I claim:

1. A water softener comprising a casing having a bed of zeolites spaced from its bottom a deflector located centrally at the bottom of the casing below the zeolites and having a cusp-like contour, a pipe leading laterally into said casing and passing downwardly centrally thereof and adapted to discharge water over the point of said cusp-like member, whereby said water is uniformly distributed across the bottom of said zeolites and may pass upwardly therethrough, a discharge pipe leading from the upper portion of said casing, means for controlling and reversing the flow of water through said casing, and means for introducing salt into said casing.

2. A water softener comprising a cylindrical casing having a cup-like bottom portion provided with a cusp-like central member, a pipe leading laterally into said casing and extending axially downwardly therethrough and discharging directly over said cusp-like member, said casing having a bed of zeolites supported above its bottom portion, a discharge pipe leading from the upper portion of said casing, a removable cap carried by said casing, piping connecting said pipes with a delivery pipe, a waste pipe and a supply pipe, and valves controlling the direction of flow of water through said casing, whereby said water may be caused to flow first in one direction and then in the other during washing of the zeolites.

In testimony that I claim the foregoing I have hereunto set my hand at Fort Wayne, in the county of Allen and State of Indiana.

V. L. TANNEHILL.
